SIGNAL ATTACHMENT FOR INDEX CARDS

Hugh N. Pitcher, Montreal, Quebec, Canada

Application July 16, 1948, Serial No. 39,141
In Canada June 30, 1948

7 Claims. (Cl. 129—16.7)

1

This invention relates to signal attachments for visible index record cards and the object is to provide means for supporting and guiding a plurality of signals so that they may be slid past each other to different indicating positions along one edge of the card.

In the preferred embodiment selected for illustration a plurality of signals are slidably supported for movement along one edge of the card by guiding means including signal separating means along which the signals are moveable so that they can be slid past each other in either direction. In the case of a card equipped with two signals, arranged in the usual signal supporting and guiding sheath extending along the lower edge of the card, the signal separating means may consist of a signal separating member arranged in the sheath so that one signal lies between the face of the card and the separating member while the other signal lies between the separating member and the front wall of the sheath. If more than two signals are employed the number of separating members may be increased to enable each signal to be slid past the remaining signals.

Another object of this invention is to provide the signals and separating members with engaging means cooperable with each other to resist accidental sliding movement of the signals in such manner as to permit the signals to be intentionally slid by hand from one point to another against the resistance of the cooperable engaging means.

The above and other objects and characteristic features of this invention will be more readily understood from the following detailed description taken in connection with the accompanying drawings, in which—

Fig. 1 is a front view of a visible index card holder with the assembled parts embodied in my invention.

Fig. 2 is a rear view of the assembly shown in Fig. 1.

Fig. 3 is a view showing a separating strip.

Fig. 4 is a view showing a sliding signal.

Fig. 5 is a sectional view taken along the section line 5—5 of Fig. 4.

Fig. 6 is a diagrammatic view of a card (in reduced proportion) employed in my invention.

Fig. 7 is a diagrammatic view of a strip (in reduced proportion) employed in my invention.

Fig. 8 is a sectional view (enlarged) taken along the section line 8—8 of Fig. 1.

Fig. 9 is a sectional view (enlarged) taken along the section line 9—9 of Fig. 1.

2

Referring more particularly to the drawings, 5 designates a conventional index card-holder consisting of a sheet of cardboard or other suitable material provided with laterally projecting end tabs 6 at its upper corners adapted to be suitably secured in pivotal retaining means of an index card tray (not shown). Card holder 5 is slotted, as indicated at 7, for the insertion of the upper corners of an index card 8 in retaining engagement with the holder. The lower marginal portion of holder 5 is fitted into a pocket forming sheath 9. Sheath 9 is formed from a suitable strip of transparent material folded upon itself to provide a closed bottom 10 and front and rear retaining walls 11 and 12 respectively. Rear wall 12 extends upwardly a substantial distance to flatly engage the rear surface of holder 5, while front wall 11 extends upwardly and has its upper end infolded to provide a downwardly projecting lip 14 which is disposed between the inner surface of front wall 11 and the front surface of card holder 5. Sheath 9 is secured about the lower marginal portion of card holder 5 by staples 15 or other suitable means which extend through

front wall 11, card holder 5 and rear wall 12 adjacent the side edges thereof. Staples 15 close

off the ends of sheath 9 in the proximity of the inturned lip 14 leaving a substantial side opening, indicated at 16, adjacent the closed bottom

10 of sheath 9.

The index card 8 to be mounted on card holder 5, has its lower marginal portion inserted in sheath 9 between front retaining wall 11 and card holder 5. The upper corners of card 8 are inserted through slots 7 for locking engagement therewith. The card may be provided along the bottom with scale readings appearing behind the transparent front wall 11 of the sheath. However, I have found it more desirable to provide a separate strip 18 having suitable scale readings thereon.

As strip 18 is usually elongated and narrow to overlie the bottom marginal portion of card 8, retaining tabs 19 are provided which extend laterally from the ends of the strip adjacent the bottom edge. Thus, when strip 18 is inserted in sheath 9 in front of card 8, tabs 19 will project beneath staples 15 into side openings 16 of the sheath to secure the strip therein.

50 A signal 20 comprising a narrow strip of stiffened material pointed at one end is folded upon itself adjacent its pointed end to provide a relatively short upturned "arrowhead" 21 and an elongated upwardly extending "tailpiece" 22. Signal 20 is arranged vertically in sheath 9 with

its "arrowhead" 21 projecting upwardly to overlie the exposed face of strip 18 and its "tailpiece" 22 interposed between the rear surface of holder 5 and sheath retaining wall 12 to project a substantial distance beyond the upper edge of wall 12.

Strip 18, card 8 and card holder 5 are provided with registering slots 24 extending upwardly from the central portion of their lower edges to provide a passageway 24a from front to rear. A signal separating member 25, consisting of an elongated strip of transparent material is arranged in sheath 9 to project through passageway 24a so that one half of the member is disposed between the rear face of holder 5 and rear retaining wall 12 of the sheath while the other half is disposed to overlie the face of strip 18 and the "arrowhead" 21 of signal 29 to separate signal 20 from the front retaining wall 11 of the sheath. Signal separating member 25 is preferably provided with a laterally projecting tongue 26 which is inserted in side opening 16 of sheath 9. The portion of member 25 which covers the front face of strip 18 is provided with an upwardly projecting marginal extension 27 to prevent that portion of the separating member from sliding through passageway 24a. Extension 27 and tongue 26 serve to secure the separating member in the sheath. A second signal 28, consisting of an elongated strip of transparent material is arranged to slide through passageway 24a so that one portion of said signal lies between the rear face of card holder 5 and separating member 25 and the other portion lies between separating member 25 and the front retaining wall 11 of sheath 9. With this arrangement it will be seen that signal separating member 25 forms separate channels for the signals 20 and 28 so that signal 28 may slide back and forth in front of strip 18 without interference from signal 20. Signal 28 is provided with an outwardly protruding bubble 29 which serves as a marker to indicate a desired point on the face of strip 18. The upper edge of bubble 29 is scored to provide a lip 30 adapted to lap around the inturned lip 14 of front retaining wall 11. The arrangement of lip 30 with lip 14 permits sliding movement of signal 28 but prevents accidental removal of the signal from the sheath. The arrangement of signal 28 in passageway 24a also serves to prevent removal of the signal from the sheath.

The surfaces of signal 28 and signal separating member 25 are provided with corrugations 34 and 35 which engage one another to cooperatively serve as means for resisting accidental sliding movement of the signal. Thus it will require a deliberate action to slide signal 28 in its channel against the resistance of cooperating corrugations 34 and 35.

In operation, the scale readings along the bottom of card 8 or preferably strip 18 may be of any suitable nature. For example, an objective for a year's turnover in business is illustrated. Assuming the year's objective to be 100%, certain average percentages are required to be attained each month to reach the year's objective. For this reason, it is desirable to place signal 20 at the required percentage for a specific month in order to determine the quota for that month. If the percentage required for the end of August is 75% by way of example, signal 20 is moved until arrowhead 21 covers that figure. Signal 28 which is readily slidable, can then be utilized to determine the progress in attaining the de-

sired quota. In order to indicate that the quota has been exceeded, it is necessary for the sliding signal 28 to pass the signal 20. With my arrangement of the signals in separate channels, the one signal can pass the other signal without interference and without disturbing the stationary signal when moving the other past it.

If it is desirable to have other progressive signals, these may be inserted in the manner set forth in connection with signal 28 and further separating members may be appropriately inserted to provide separate channels for each of the additional signals.

Although I have called for a slotted passageway 24a through strip 18, card 8 and card holder 5, various modifications of this arrangement could readily be resorted to. For example, the slot 24 through holder 5 as well as card 8 could be eliminated. In such cases the extension of signal 28 and the projection of signal separating member 25 will extend between the card and holder or alternatively the strip and card. Then again it may not be desirable to utilize the passageway 24a but to extend the separating member 25 and signal 28 between the front wall of the sheath and strip 18. In this event any suitable retaining means could be employed such as one or more additional bubbles which are adapted to engage the inturned lip 14 of front wall 11.

Having described what I now believe to be the preferred embodiment of this invention, it will be understood that various modifications and alterations may be resorted to without departing from the scope and spirit of the invention as defined in the appended claims.

I claim:

1. In a device of the character described, a card holder, a pocket member comprising a transparent strip of material folded upon itself to form a closed bottom and upwardly projecting front and rear retaining walls, said pocket member being arranged along one edge of the card holder to enclose the marginal portion thereof, an index card adapted to be mounted on said card holder with a marginal portion of said card fitted in the pocket between the front retaining wall and the card holder, said card and card holder being provided with a slotted passageway within the pocket member, a signal comprising a narrow strip of stiffened material folded upon itself to provide a relatively short upturned indicator and an elongated upwardly extending tailpiece, said signal being arranged vertically for sliding movement in the pocket member with its indicator end projecting upwardly to overlie the exposed face of the card within the pocket and its tailpiece interposed between the rear surface of the card holder and the rear wall of the pocket to project a substantial distance beyond the upper edge of the wall, a transparent signal separating member arranged in said pocket the full length thereof and projecting through said slotted passageway so that one portion of said separating member is disposed between the rear face of the card holder and the rear wall of the pocket and the remaining portion is disposed to overlie the exposed face of said card and the indicator portion of the signal, and a second signal consisting of an elongated strip of transparent material arranged horizontally in said pocket for slidable movement across the face of said card, said second signal being slidable through the card and card holder passageway so that one portion of said second signal lies be-

tween the rear face of said card holder and the portion of the signal separating member at the rear of the card holder, and the other portion lies between the portion of the signal separating member in front of the card and the front wall of said pocket to permit sliding movement of said second signal to any non-overlapping position relative to the first mentioned signal across the face of the card and to pass said first mentioned signal in overlapping relation without interference from said first signal.

2. An arrangement for an index device, comprising an index-card receiving sheath substantially U-shaped in cross-section, a slotted member arranged in and extending substantially the full length of said sheath, said member being provided with a slot located at a point spaced a substantial distance from the vertical margins of said member, said slot being positioned between and covered by the sides of the sheath, a stationary signal-separating strip removably fitted in and extending substantially the full length of said sheath, said strip passing through said slot, a signal slidably arranged in the sheath to travel over one side surface of the portion of the slotted member located at one side of said slot, said signal being arranged to travel in a guideway formed by and between said surface of the slotted member and an overlying opposing portion of said strip and a second signal slidably arranged in said sheath to travel over the same surface portion of the slotted member which is traversed by the first signal, said second signal having an elongated body portion passing through said slot and being arranged to travel in a guideway formed by and between the signal-separating strip and the side of the sheath overlying said surface of the slotted member which is traversed by the signals.

3. In an index device arrangement as set forth in claim 2, an index card secured to said card-holding sheet and having its lower portion fitted in said sheath and provided with a slot registering with the slot in the card-holding sheet and receiving the signal-separating strip therethrough.

4. An arrangement for an index device, comprising a card-holding sheet provided with a slot located in the lower portion thereof at a point spaced a substantial distance from the side edges of the sheet, an index-card receiving sheath, substantially U-shaped in cross section, embracing and extending along the full length of the lower portion of said sheet with the sides of the sheath overlying said slot, said sheath being secured at its ends to said sheet, an index card secured to said card-holding sheet and having its lower portion fitted in said sheath and provided with a slot registering with said first-mentioned slot, a stationary signal-separating strip removably fitted in and extending substantially the full length of the sheath, said strip passing through the registering slots of the card-holding sheet and the index card so that the exposed surface of the lower portion of the index card located at one side of the slots is covered by the portion of the strip located at the same side of the slots, a signal arranged to slide in the sheath between the said exposed surface of the index card and the covering portion of the signal-separating strip, and a second signal arranged to slide in the sheath between the last-mentioned portion of the signal-separating strip and the side of the

sheath overlying the said exposed surface of the index card, said second signal including an elongated body portion passing through said slots.

5. An arrangement as set forth in claim 4 including an indicia bearing strip arranged in and extending the full length of the sheath, said indicia bearing strip being positioned between the first signal and the exposed surface of the index card traversed by said signal and being provided with a slot registering with the slots in the sheet and the index card and receiving the signal-separating strip therethrough.

6. An arrangement for an index device, comprising a card-holding sheet adapted to support an index card on the front side thereof, an index-card receiving sheath, substantially U-shaped in cross section, embracing and extending along the full length of the lower portion of said sheath, said sheath being secured at its ends to said sheet, an index card fitted against the front side of said card-holding sheet and having its lower portion fitted in said sheath, an indicia bearing strip removably fitted in and extending the full length of the sheath between the front side of the index card and the front side of said sheath, said indicia bearing strip being provided with a slot located a substantial distance from its vertical edges and within the sheath, a stationary signal-separating strip removably fitted in and extending substantially the full length of the sheath, said strip passing through the slot in the indicia bearing strip so that the exposed surface of the portion of the indicia bearing strip located at one side of the slot is covered by the portion of the signal-separating strip located at the same side of said slot, a signal arranged to slide in the sheath between the said exposed surface of the indicia bearing strip and the covering portion of the signal-separating strip, said signal being shaped to embrace the lower edge of said sheet with an end portion of the signal projecting above the sheath to provide an accessible tailpiece by means of which the signal may be moved to various positions of adjustment along the sheath, and a second signal arranged to slide in the sheath between the last-mentioned portion of the signal-separating strip and the side of the sheath overlying the exposed surfaces of the index card and the indicia bearing strip, said second signal having an elongated body portion passing through the slot in the indicia bearing strip.

7. An arrangement as set forth in claim 6, with a slot formed in the lower portion of said index card to match said slot formed in the indicia bearing strip and such that the concealed portions of the signal-separating strip and the second signal operate in the space bounded by the rear side of the index card and the front side of the card holding sheet.
